ENDLESS CONVEYORS

Joseph E. Sheehan, Sr., Flint, Mich., assignor to
Mary Ann Sheehan, Detroit, Mich.
Filed July 10, 1961, Ser. No. 122,783
10 Claims. (Cl. 198—158)

This invention relates to endless conveyors, and particularly to such conveyors as are adapted to maintain a load-carrying position of load-carriers relative to their path of travel, or to predeterminedly alter such position to an unloading position about an axis of rotation substantially transverse to said path of travel.

An object of the invention is to provide spaced, similar, parallel tracks, and at least one load-carrier unit adapted for travel along said tracks and rotatable about said axis to effect said change of position.

Another object is to rigidly mount on said unit a control element rotatable about said axis to rotate said carrier thereabout to maintain or change said position, and to further provide an actuator to act upon and rotate said control element.

Another object is to provide a guideway, following a normal path, in association with at least one track and to provide means on said actuator to follow the guideway; and to form said guideway with abnormal contours to position said means to act on said control element and to rotate said carrier, when said means passes through said abnormal contours.

Another object is to provide track-followers for the carrier unit and to adapt a surface of said track to act upon said track-follower to resist undesired rotation, and to adapt an extent of said track surface corresponding with an extent of said abnormal contour to afford said desired rotation.

These and various other objects are attained by the construction hereinafter described and illustrated by the accompanying drawings, wherein:

FIG. 1 is a rear elevational view of my invention showing a carrier in a load-carrying position and a carrier in an unloading position.

FIG. 2 is a side elevational sectional view of the invention on line 2—2 of FIG. 1, showing said carriers.

FIG. 3 is a side elevational view in section on line 3—3 of FIG. 1, showing additional carriers to illustrate the governing effect of the guideway.

FIG. 4 is a sectional view on a larger scale on line 4—4 of FIG. 3 rotated 90° clockwise, showing details of the track-follower, control element, and actuator.

FIG. 5 is a partial sectional view on line 5—5 of FIG. 4, rotated 90° clockwise.

FIG. 6 is a partial sectional view on line 6—6 of FIG. 4, rotated 90° counter clockwise.

FIG. 7 is a partial sectional view on the same line as FIG. 3, but showing a modification of the carrier rotating means.

In these views, the reference character 1 designates a pair of vertically elongated, laterally spaced side members having vertical spans 1a and horizontal spans 1b. A brace 2 surmounts and rigidly interconnects the upper horizontal span, and a support 3 elevates and further interconnects the device at the lower horizontal spans.

Each side member 1 is similarly formed with a track 4 and a guideway 5, the purpose of which is hereinafter explained. The two parts 6 and 7 of each side member are joined by a plate 8, cut to the contour of said members (as shown in FIGS. 2 and 3), and which also serves to enclose the guideway.

Ribs 9 rigidly mount bearings 10 in which are journaled shafts 11 to rigidly carry sprockets 12, having hubs 12a. Said hubs are secured on the shafts as by set screws (not shown) to bear against the inner faces of the ribs

2

9 and resist axial movement of the shafts 11. An endless chain 13 is mounted upon said sprockets. Power may be applied to any one of said shafts and in any convenient conventional manner to rotatively drive such 5 shaft, its sprockets, and the chains.

Dogs 14 are interspersed as required between links of the chain 13 to drive carrier units 15. Each unit comprises axially aligned shafts 16; each such shaft has one end rigidly received in a respective lug 17, which lug is 10 secured, as by welding, to a carrier plate 18. Said shaft passes through said dog to be driven thereby, and has its other end rigidly mounting a track-follower assembly. Said assembly includes a rectangular plate 19, on which are mounted wheels 20 journaled on axles 21 and rolling on the opposed surfaces of the track 4. Said axles are 15 equally spaced from and about the longitudinal axis of the shaft 16.

The axles mount a second rectangular plate 22, which in turn carries a short shaft 23 in permanent axial alignment with the shafts 16. A control element 24 is mounted on the shaft 23, the function of such elements being explained below. Said control element carries an actuator, including a trolley 25 received in a recessed runway 26 formed in the control element. Said trolley being 20 provided with wheels 27 to facilitate travel longitudinally of said runway. A cover plate 28 secured to the control element retains the trolley in the runway, and is slotted at 29 to afford passage to an axle 30 of said actuator to mount a wheel 31 for travel in said guideway 4, whereby, 25 as hereinafter explained, the actuator acts on the control element to rotate the carrier about the longitudinal axis of the shafts 16.

As best seen in FIG. 3, the guideway follows a path normally determined by the necessity to maintain the 30 carrier plate 18 in a horizontal, load-carrying position. However, in the construction as illustrated, as the carrier descends (on the right in FIGS. 2 and 3) it is desired to tip the carrier unit ninety degrees for the purpose of unloading the carrier plate 18.

To effect such tipping, the entire unit is caused to rotate about the said longitudinal axis of the shafts 16. The guideway 5 departs from its normal path to follow an abnormal contour 33, and the track is recessed, as at 35. Thus, the contour 33 tends to draw the guide wheel 31 toward the right, forcing it to follow a longer path than the track-follower 19, 20, 21, 22, as the chain 13 drives said track-follower in a substantially rectilinear path of travel. This longer rightwardly directed travel of the guidewheel causes the trolley to apply pressure 40 upwardly and increasingly rightwardly within the control element to rotate said control element, and consequently the rigidly connected carrier unit, ninety degrees to empty the carrier plate 18 of its load. Once the wheels 20 engage the track surfaces again, and the guideway is 45 aligned with the track, the actuator will normally drop and until the trolley reaches the bottom of said runway as 50 seen in FIG. 3.

The actuator remains in this position, due to the respective paths followed by the track and guideway, until the 55 guide wheel encounters the portion 43 of the guideway curving toward the lower horizontal span 1b. This curvature draws said guide wheel and trolley to uppermost position of the trolley before the track-follower fully emerges from the track in the vertical span. Thus, when 60 the axle 30 passes through a point of alignment with the axis of rotation, the wheels 20 are still engaged with said track to resist undesired rotation of the carrier, which could occur at said point, if the wheels were free of the track. As said track-follower enters the track in the 65 lower horizontal span 1b, a downwardly inclined abnormal contour 34 draws the guide wheel downwardly to its lowest position, because the track surface at this point 70

is not recessed, and thus restrains the wheels 20 against rotation.

The subsequent upwardly inclined portion of the contour 34 imposes a longer path of travel on the guide wheel than is followed by the track-follower, and the track is here recessed at 36, which allows the control element to respond to a rearwardly and increasingly upwardly directed pressure of the trolley to rotate said control element and the rigidly associated carrier unit until the carrier plate 18 is returned to a horizontal position for loading. Any type of reloading means that is practical may be employed with the construction.

Said rotation to unload the plate may be accomplished more rapidly than as above described, by disposing a fixed cam 38 in the path of the control element at the point at which such rotation is desired (FIG. 7). Engagement with the cam forces the control element to rotate in the desired direction. To afford such rotation, the track must be recessed, as at 36, and the guideway must align itself with the track, as seen in FIG. 7, so that the axle of the guide wheel is aligned with the axis of the shafts 16. Otherwise, said guide wheel would be offset from the axis of said shaft 16 as best shown in FIG. 6, and would tend to resist rotation.

The path of the guideway relative to that of the track is intended to subject the guide wheel as constantly as possible to the drive of the chain, whereby control may be maintained over the position of the axle 30 relative to the axis of the shaft 16. Thus, the upwardly inclined contour 37 (FIGS. 2 and 3) draws the guide wheel to the left so that it will be drawn by the control element (responsive to the chain's drive) across the upper horizontal span 1b. The only point in its travel where the guide wheel cannot be subjected to said drive and control is the aforesaid extent of travel from the point at which full rotation has occurred at track recess 35, to the curvature 43 of the guideway and the trolley may drop to the bottom of the runway as aforesaid.

As the track is omitted at the juncture of each vertical and horizontal span of the side members reliance is placed on an offset relation of the axis of the shaft 16 and the axis of the guide wheel axles 30 to prevent undesired rotation of the carrier unit. Such offset relation (best illustrated in FIG. 4) is induced, of course, by the guideway contours 41, 42, 43 and 44, which follow paths non-aligned with the paths of the tracks.

It may here be noted that if it is desired, the recess of the track may be extended appropriately, and the abnormal contour of the guideway, such as at 33, may return to a vertical course before it becomes aligned with the track as shown in FIGS. 2 and 3. This would dispose the axle 30 in a higher plane than the shafts 16, and would tend to maintain the carrier, while such situation continued, at any desired angle, which angle would be predetermined by the spacing of the longitudinal center of the guideway from and parallel to that of the track. As said track would, in such case, not act to restrain rotation of the carrier, such restraint would be imposed by the juxtaposition of the shafts 16 as they pass through the dogs, and of the said axle 30 mounting said guide wheel.

The aforesaid arrangement of the track-follower allows two of the wheels 20 to engage each of the opposed surfaces of the track, whereby said track surfaces impose said restraint against rotation or rocking of the carrier on the axis of the shafts 16. While four wheels are shown, the same result may be obtained with additional wheels on axles equally spaced from and about the axis of shafts 16.

The four wheel arrangement is suited as seen above to rotation of ninety degrees. With six wheels, suitably disposed, the angle of rotation could be reduced to sixty degrees, and still maintain two wheels in contact with

the track surfaces before and after each rotation of sixty degrees.

Obviously, the described construction may be employed for many purposes, and its proportions may be adapted to many environmental conditions. For example, it may serve to carry parts to production lines, or to carry ores from mines, particularly up steep inclines, not suited for a belt type conveyor. The carrier plate 18 would, of course, be designed for the job it would have to do.

10. What I claim is:
1. In an endless conveyor, a pair of laterally spaced parallel tracks, one or more carrier units adapted for travel along said tracks and rotatable between alternative carrying and unloading positions about an axis extending through said carrier and substantially transverse to the direction of said travel, said unit including a carrying member, a support member disposed between the tracks and rigidly supporting said carrying member, track-followers mounted on the support member and respectively positioned for travel along the respective tracks, drive means acting on the carrier unit to effect such travel, a control element mounted on the track follower and actuatable to rotate said carrier unit about said axis, said track follower including a plurality of wheels at least two of which roll on a surface of the track, said surface acting on said wheels to resist said rotation of the carrier unit, means effective on said control element to induce desired rotation of the carrier unit about said axis between said positions, and said track being adapted to afford said rotation.
  2. In an endless conveyor as set forth in claim 1, said last mentioned means being a cam element disposed in the path of travel of said control element for engagement by said control element, whereby said element is cammed into desired rotation about said axis, and said track surface is recessed to remove said resistance to rotation.
  3. In an endless conveyor, a pair of laterally spaced parallel tracks, one or more carrier units adapted for travel along said tracks and having an axis of rotation extending through the carrier and substantially transverse to the direction of said travel, said unit including a carrying member, a support member disposed between said tracks and rigidly supporting the carrying member, track-followers mounted on the support member and respectively positioned for travel along the respective tracks, drive means acting on the carrier unit to effect such travel, a control element mounted on a track-follower and actuatable to rotate said carrier unit about said axis of rotation, a guideway associated with one of the tracks and normally following a path parallel to that of said tracks, an actuator mounted on the control element to travel in said guideway, said guideway being formed with an abnormal contour, whereby said actuator responds to its travel along said contour to act on the control element to effect desired rotation of the carrier unit about said axis between alternative load carrying and unloading positions.
  4. In an endless conveyor as set forth in claim 3, a track surface normally engaging said track-follower to resist undesired rotation about said axis, and said surface being formed with a recess to afford said desired rotation responsive to said actuator.
  5. In an endless conveyor as set forth in claim 4, said control element being elongated, and said actuator being mounted thereon for travel longitudinally thereof responsive to travel of the actuator along said abnormal contour to position said actuator to act on the control element to effect desired rotation, and said recess in the track surface being disposed to correspond to said position.
  6. In an endless conveyor as set forth in claim 5, said track follower including a plurality of wheels revoluble on axes spaced from and about the axis of rotation of the carrier unit, said wheels rolling on said track surface and encountering said resistance.
  7. In an endless conveyor as set forth in claim 5, said

actuator including a shaft, and a wheel revoluble on said shaft to roll in said guideway.

8. In an endless conveyor as set forth in claim 7 the last mentioned shaft mounting a trolley spaced from said guide wheel, and said control element being formed with a longitudinally extending runway to receive said trolley for said longitudinal travel.

9. In an endless conveyor as set forth in claim 8, means to restrain said trolley from escape from said runway, said means being adapted to afford said travel of the trolley and said last mentioned shaft.

10. An endless conveyor as set forth in claim 9, said

drive means including an endless chain, means, including a driven sprocket to support said chain, means to drive said sprocket, and means interconnecting the chain with said carrier unit to transmit said drive to said carrier unit.
